UNITED STATES PATENT OFFICE.

GEORGE W. PRIEST, OF WILMINGTON, DELAWARE, ASSIGNOR TO E. I. DU PONT DE NEMOURS AND COMPANY, OF WILMINGTON, DELAWARE, A CORPORATION OF DELAWARE.

METHOD FOR PRODUCING LINOLEUM AND PRODUCT THEREOF.

1,334,049.

Specification of Letters Patent. Patented Mar. 16, 1920.

No Drawing.

Application filed August 8, 1917. Serial No. 185,015.

To all whom it may concern:

Be it known that I, GEORGE W. PRIEST, of Wilmington, in the county of New Castle, and in the State of Delaware, have invented 5 a certain new and useful Improvement in Methods for Producing Linoleum and Product Thereof, and do hereby declare that the following is a full, clear, and exact description thereof.

10 My invention relates to a new linoleum and a process of making the same.

The object of my invention is to provide a linoleum article containing polymerized Chinese wood oil or tung oil and a polymerized product of the coumarone or indene group of compounds combined in an advantageous manner.

Further objects of my invention will appear from the detailed description thereof 20 contained hereinafter.

I have found that when previously polymerized Chinese wood oil or tung oil is ground together in any suitable machine, as for example a machine containing friction 25 rolls, with a polymerized product of the coumarone or indene group of compounds at a temperature of 100° C. or below a material is obtained which has different characteristics as to its consistency, combining 30 qualities, solubility, etc. which make it more useful as a cement than in the case where the polymerized product of the coumarone or indene group of compounds is added to the Chinese wood oil when heated 35 to above 100° C.

While my invention is capable of being carried out in many different ways, I shall describe only one example thereof herein-after.

40 In order to carry out my process I may for example heat two parts of Chinese wood oil or tung oil to 265° C., so as to polymerize the same and produce a jelly-like material. The material thus obtained is allowed to cool and I then mix therewith one 45 part of a polymerized product of the coumarone or indene group of compounds and grind the same together at a temperature of 100 C. or below thus producing a composition which is elastic, adhesive, coherent 50 and light in color.

This composition may be used for lino-

leum cement by mixing with suitable proportions of pigment, ground cork, or woodmeal, as for example—

55

Tung oil coumarone resin composition	50 parts.
Pigment	20 "
Ground cork or woodmeal	50 " 60

and applying to a fabric by means of pressure. The material may also be used for cementing materials of other kinds together, and on fabrics of all kinds.

While I have described my invention 65 above in detail, I wish it to be understood that many changes may be made therein without departing from the spirit of the same.

What I claim is:—

70

1. The process which comprises mixing together an oil and a polymerized product of the coumarone or indene group of compounds at a temperature not above 100° C. and so applying the mixture to a fabric 75 layer as to cause it to adhere thereto.

2. The process which comprises mixing together an oil and a polymerized product of the coumarone or indene group of compounds at a temperature not above 100° C., 80 and so applying the mixture together with ground cork to a fabric layer as to cause it to adhere thereto.

3. The process which comprises mixing together polymerized Chinese wood oil and 85 a polymerized product of the coumarone or indene group of compounds at a temperature not above 100° C., and so applying the mixture to a fabric layer as to cause it to 90 adhere thereto.

4. The process which comprises mixing together polymerized Chinese wood oil and a polymerized product of the coumarone or indene group of compounds at a temperature not above 100° C., and so applying the 95 mixture together with ground cork to a fabric layer as to cause it to adhere thereto.

5. An article of manufacture comprising an oil mixed with a polymerized product of the coumarone or indene group of compounds, and a fabric layer carrying the same. 100

6. An article of manufacture comprising polymerized Chinese wood oil mixed with a

polymerized product of the coumarone or indene group of compounds, and a fabric layer carrying the same.

7. An article of manufacture comprising
5 polymerized Chinese wood oil mixed with a polymerized product of the coumarone or indene group of compounds and ground cork mixed therewith, and a fabric layer carrying the same.

- 10 8. An article of manufacture comprising

a thickened oil mixed with a polymerized product of the coumarone or indene group of compounds, and a fabric layer carrying the same.

In testimony that I claim the foregoing 15
I have hereunto set my hand.

GEORGE W. PRIEST.
